RAILWAY SIGNALING

Howard A. Thompson, Edgewood, Pa., assignor
to The Union Switch & Signal Company, Swiss-
vale, Pa., a corporation of Pennsylvania

Application September 18, 1936, Serial No. 101,467

9 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three sections in the rear of an occupied section. Each distinctive control is effective to cause a corresponding 10 aspect of the associated wayside signal whereby there is produced a three-block, four-indication, system of signaling.

I will describe one form of apparatus embodying my invention, and will then point out the 15 novel features thereof in claims.

In the accompanying drawings, Figs. 1A and 1B are diagrammatic views which when placed end to end in the order named illustrate one form of apparatus embodying my invention.

20 Referring to the drawings, the reference characters 1 and 2 designate the rails of a stretch of railway track along which traffic normally moves in the direction indicated by the arrows. These rails are divided by insulated joints 3 into a plurality of track sections W—X, X—Y, and Y—Z.

As here shown, each track section is divided by insulated joints 3 into at least two sub-sections 1T, 2T, 3T, 4T, etc. Each sub-section is 25 provided with a track circuit which includes a track battery 10 connected across the rails at one end of the sub-section and a track relay, designated by the reference character TR with a prefix the same as the numerical prefix in the 30 reference character of the associated sub-section, connected across the rails at the other end of the sub-section.

To govern the passage of trains through the 35 stretch of railway, a wayside signal designated 40 by a suitable distinguishing reference character, is provided for each track section. Each of these signals includes an upper indication unit U and a lower indication unit L. These units may take any one of several forms of signal mechanism 45 such as semaphore, color light, searchlight, or position light. As here shown, each upper unit U is a semaphore arm capable of assuming a horizontal or "stop" position, a 45° or "caution" position, and a vertical or "proceed" position; and 50 each lower unit L is a caution lamp Y capable of displaying a yellow light.

Operatively connected with each semaphore arm U is a contact 17 and a pair of pole changing contacts 18 and 19. Contact 17 is in engagement with contact 20 at all times except when the

semaphore arm is in the vertical position. Pole changing contacts 18 and 19 are in engagement with contacts 21 and 22, respectively, whenever the semaphore arm is in its 45° position or in its vertical position or at any point between these two positions, and are in engagement with contacts 23 and 24, respectively, whenever the semaphore arm is at any point below the 45° position. 5

Each semaphore arm U is provided with a lamp E which when lighted provides supplementary color light indications corresponding to the 10 positions of the associated semaphore arm.

For controlling the associated signal, each section is provided with a polarized signal control relay, a neutral signal control relay, and an auxiliary relay designated by the reference characters HD, J, and JP, respectively, each with a prefix the same as the reference character of the associated signal. 15

For controlling the associated relays HD and J, each section is provided with a pair of conductors each of which extends to the signal next in advance and each of which includes a front contact of each of the associated track relays. 20

Each section is provided with an operating battery the terminals of which are designated by 25 the reference characters B1 and C1 and each section is provided with a line battery designated by the reference character 11. Each line battery 11 is provided with a low voltage terminal, a high voltage terminal, and a common return 30 terminal designated by the reference characters B1, B2, and C, respectively.

Each relay HD is connected to the associated 35 pair of conductors by signal contact 17—20 of the associated signal. Each relay J is connected to the associated pair of conductors through a resistor 16.

Each relay JP is governed by the associated 40 relay J. For example, relay 12JP is governed by a circuit which includes front contact 25 of relay 12J, so that relay 12JP will be energized or deenergized when relay 12J is energized or deenergized.

As will be explained more in detail hereinafter, 45 the pair of conductors for each section is at times supplied with energy of a relatively low value and at other times is supplied with energy of a relatively high value. The pickup value of the relays HD is such that these relays will become 50 picked up upon receiving energy of either value whereas the pickup value of the relays J is such that these relays will become picked up only upon receiving energy of the higher value.

The signal pole changing contacts 18 and 19 55

and the relays HD and JP control the magnitude and direction of the energy supplied to the line conductors for the section next in the rear.

For controlling the signal lamps E and Y, each section is provided with an approach lighting relay designated by the reference character ER with a prefix the same as the reference character of the associated signal. The relays ER are connected in series with the line conductors for the section next in rear and therefore are energized at all times except when that line circuit is open. That is, the approach lighting relays ER become released to energize the associated lamp E and the control circuit for the associated lamp Y only when the section immediately to the rear of the signal with which such lamps are associated becomes occupied by a train.

The relays HD, J, and JP control the upper unit U and the lower unit L of the associated signal in the following manner: When the line circuit is opened so that all relays are deenergized (see signal 15), both semaphore arm U and lamp Y are deenergized so that signal 15 is displaying its semaphore arm in the horizontal position to indicate "stop". When the relay HD is energized in the reverse direction (see signal 14), a caution circuit for the semaphore arm U of that signal is closed over a path which passes from terminal B0 over front contact 26 of relay 14HD, semaphore arm U, and front contact 27 of relay 14HD to terminal C0. Semaphore arm U of signal 14, therefore, is in the caution position to indicate "approach next signal prepared to stop". When relay HD is energized in the normal direction (see signal 13), the caution circuit for semaphore arm U remains closed over front contacts 26 and 27 of relay 13HD and a circuit is established for the lamp Y of the lower unit L of that signal. This circuit passes from terminal B0 over back contact 28 of relay 13ER, back contact 29 of relay 13J, front contact 30 of relay 13HD, normal polar contact 31-32 of relay 13HD, and lamp Y to terminal C0. Signal 13, therefore, is displaying its upper semaphore arm U in the caution position and a circuit for lamp Y is established so that when relay 13ER becomes released by a train approaching signal 13 in section W-X, this signal will display its semaphore arm in the caution position over a yellow light to indicate "approach next signal at medium speed". When relay HD is energized in the normal direction and relays J and JP also are energized (see signal 12), the caution circuit for the upper semaphore arm U will remain closed over front contacts 26 and 27 of relay HD and a proceed circuit for the semaphore arm U will be closed over a path which passes from terminal B0 over front contact 26 of relay 12HD, front contact 33 of relay 12JP, semaphore arm U, and front contact 27 of relay 12HD to terminal C0. Signal 12, therefore, is displaying its semaphore arm in the vertical position to indicate "proceed at normal speed". When the semaphore arm U of signal 12 attained its proceed position, signal contact 17-20 became opened so that relay 12HD is released. Consequently, the caution and clear circuits for upper semaphore arm U are disconnected from the terminals B0 and C0 of the operating battery and are connected directly to the line conductors for the section W-X over the back points of contacts 26 and 27 of relay 12HD.

As here shown, a train K is indicated diagrammatically in the section immediately to the right of location Z so that the signal 15 and associated relays are all deenergized.

When signal 15 and associated apparatus is in this condition, relay 14HD is energized in the reverse direction by energy of a relatively low value over a circuit which passes from terminal B1 of battery 11 at signal 15, through signal contact 19-24, back point of contact 34 of relay 15JP, front contact 35 of relay 5TR, front contact 36 of relay 5TR, relay 14HD, contact 17-20 of signal 14, front contact 37 of relay 5TR, front contact 38 of relay 6TR, back point of contact 39 10 of relay 15JP, contact 18-23 of signal 13, and relay 15ER to terminal C.

When relay 14HD is energized in the reverse direction, so that semaphore arm U of signal 14 is in the caution position, relay 13HD is energized 15 in the normal direction by energy of relatively low value over a path which passes from terminal B1 of battery 11 at signal 14, through reverse polar contact 40-41 of relay 14HD, front contact 42 of relay 14HD, contact 18-21 of signal 14, back point of contact 43 of relay 14JP, front contact 44 of relay 4TR, front contact 45 of relay 3TR, contact 17-20 of signal 13, relay 13HD, front contact 46 of relay 3TR, front contact 47 of relay 4TR, back point of contact 48 of relay 14JP, contact 19-22 of signal 14, and relay 14ER to terminal C.

When only relay 13HD is energized in the normal direction so that the semaphore arm U remains in its caution position, both relays 12HD 30 and 12J are energized in the normal direction by energy of relatively high value. The circuit for relay 12HD may be traced over a path which passes from terminal B2 of battery 11 at signal 13, through normal polar contact 46-49 of relay 13HD, front contact 50 of relay 13HD, contact 18-21 of signal 13, back point of contact 51 of relay 13JP, front contact 52 of relay 2TR, front contact 53 of relay 1TR, contact 17-20 of signal 12, relay 12HD, front contact 54 of relay 1TR, front contact 55 of relay 2TR, back point of contact 56 of relay 13JP, contact 19-22 of signal 13, and relay 13ER to terminal C. The circuit for relay 12J passes over the same path as just traced for relay 12HD except that back contact 59 of relay 12JP should be substituted for relay 12HD and signal contact 17-20.

When relay 12J is energized so that relay 12JP also is energized, the line conductors for the section next in rear of location W are supplied with energy in the normal direction of relatively high value over front points of contacts 57 and 58 of relay 12JP so that the signal (not shown) associated with such conductors will be in condition to display the normal proceed indication.

The resistors 16, connected in series with the relays J, are of such value that the normal current flowing in such relays is just sufficient to hold the relays picked up. The relays J, therefore, will be certain to become released when the energization of the associated line conductors is changed from the high value to the low value. A shunt path including a back contact 59 of the associated relay JP is provided around the corresponding resistor 16 in order that the relay J, when released, will receive sufficient energy for pickup. The slow pickup characteristic of the relays JP is provided to insure that the shunt path will remain closed until such time as the associated relay J becomes picked up. While the resistors 16 are here shown external to the associated relay J, these resistors may, if desired, be included as a portion of the relay winding.

Furthermore, when the energization of the line 75

conductors changed from the high value to the low value to provide a more restrictive indication, such line conductors are momentarily disconnected from the source of energy so that the 5 associated relay J will be even more certain to release. For example, when the direction of energization of the relay 13HD is changed from normal to reverse to change the energization of the line conductors for the section W—X from 10 the high value to the low value, front contact 50 of relay 13HD will become momentarily opened to disconnect energy from the line conductors for the section W—X.

Although I have herein shown and described 15 only one form of apparatus embodying my invention, it is understood that various changes and modifications may be made therein within the scope of the appended claims without departing from the spirit and scope of my invention. 20

Having thus described my invention, what I claim is:

1. In combination, a section of railway track, a pair of conductors for said section, means for 25 supplying said pair of conductors with energy of relatively low value in the reverse direction or with energy of said relatively low value in the normal direction or with energy of relatively high value in accordance with traffic conditions in advance of said section, a polarized relay responsive to energy of either value receiving current from said pair of conductors, a neutral relay responsive only to energy of said high value also receiving current from said pair of conductors, 30 a repeating relay for said neutral relay, a signal for said section comprising a first indication unit and a second indication unit, said first indication unit being a semaphore arm capable of assuming a stop and a caution as well as a proceed 35 position and said second indication unit being a lamp, a caution circuit for said semaphore arm including a front neutral contact of said polarized relay, a proceed circuit for said semaphore arm including a front neutral contact of said polarized relay and a front contact of said repeating relay, and a circuit for said lamp including a front neutral and a normal polar contact both of said polarized relay as well as a back contact of said neutral relay.

2. In combination, a forward and a rear section of railway track, a polarized relay and a neutral relay for said forward section, means effective when the forward section is unoccupied to energize only said polarized relay in the reverse direction or only said polarized relay in the normal direction or both said relays according to traffic conditions in advance of said forward section, a pair of conductors for the rear section controlled by traffic conditions in that section, 50 means effective to supply said conductors with energy of relatively low value in the reverse direction when both said relays are deenergized, means effective to supply said conductors with energy of said relatively low value in the normal direction when said polarized relay only is energized in the reverse direction, means effective to supply said conductors with energy of a relatively high value when said polarized relay only is energized in the normal direction as well 55 as when said neutral relay is energized, and traffic governing means for the rear section receiving energy from said pair of conductors and selectively responsive to the value and direction of the current received therefrom.

3. In combination, a forward and a rear sec-

tion of railway track, a polarized relay and a neutral relay for said forward section, means effective when the forward section is unoccupied to energize only said polarized relay in the reverse direction or only said polarized relay in the normal direction or both said relays according to traffic conditions in advance of said forward section, a repeating relay which becomes energized or deenergized according as said neutral relay is energized or deenergized, a signal for the forward section governed by said polarized relay and by said neutral relay, a pole changer having a contact which is closed when said signal is displaying a stop indication and another contact which is closed when said signal is displaying a proceed indication, a pair of conductors governed by traffic conditions in the rear section, means for supplying said conductors with energy of relatively low value in the reverse direction including said one contact and a back contact of said repeating relay, means for supplying said conductors with energy of said relatively low value in the normal direction including said other contact and a back contact of said repeating relay as well as a reverse polar contact of said polarized relay, means for supplying said conductors with energy of relatively high value including said other contact and a normal polar contact of said polarized relay as well as a back contact of said repeating relay, 30 means for also supplying said conductors with energy of said relatively high value including a front contact of said repeating relay, and traffic governing means for the rear section receiving energy from said pair of conductors and selectively responsive to the direction and value of the current received therefrom.

4. A railway signal system comprising a stretch of track divided into sections, a track circuit including a track relay for each section, a pair of line conductors for each section each including a front contact of said track relay, means for each section for supplying the pair of conductors for the section next in rear with energy of relatively low value in one direction or with energy of said relatively low value in the other direction or with energy of relatively high value in accordance with traffic conditions in advance, a polarized relay for each section responsive to energy of either value receiving current from the associated conductors, 40 a neutral relay for each section responsive only to energy of said high value also receiving current from the associated conductors, a signal for each section, means effective when only the polarized relay of a section is energized in said one direction to cause the associated signal to display a particular indication, means effective when only the polarized relay of a section is energized in said other direction to cause the associated signal to display a different indication, and means effective when both relays of a section are energized to cause the associated signal to display still a different indication.

5. In combination, a stretch of railway track divided into sections each provided with a track circuit including a track relay, a pair of conductors for each section each including a front contact of the associated track relay, means effective when one section is occupied to supply the conductors for the section next in rear of such occupied section with energy of a particular magnitude and direction, means then effective to supply the conductors for the section second in rear of such occupied section with energy of the same magnitude but in the other direction, means then

effective to supply the conductors for the section third in rear of such occupied section with energy of different magnitude, and traffic governing means for each section receiving energy from the associated pair of conductors and selectively responsive to the direction and value of the current received therefrom.

6. In combination, a forward and a rear section of railway track, a polarized relay and a neutral relay for said forward section, means effective when the forward section is unoccupied to energize only said polarized relay in the reverse direction or only said polarized relay in the normal direction or both said relays according to traffic conditions in advance of said forward section, a pair of conductors for the rear section controlled by traffic conditions in that section, a source of current having a high voltage terminal and a low voltage terminal, means effective to connect said conductors in one direction with said low voltage terminal when both said relays are deenergized, means effective to connect said conductors in the other direction with said low voltage terminal when said polarized relay only is energized in the reverse direction, means effective to connect said conductors with said high voltage terminal when said polarized relay only is energized in the normal direction or when said neutral relay is energized, and traffic governing means for the rear section receiving energy from said pair of conductors and selectively responsive to the value and direction of the current received therefrom.

7. In combination, a stretch of railway track divided into sections each provided with a track circuit including a track relay, a pair of conductors for each section each including a front contact of the associated track relay, means effective when one section is occupied to supply the conductors for the section next in rear of such occupied section with energy of a relatively low value in one direction, means then effective to supply the conductors for the section second in rear of such occupied section with energy of said relatively low value in the other direction, means

then effective to supply the conductors for the section third in rear of such occupied section with energy of relatively high value in the said other direction, and traffic governing means for each section receiving energy from the associated pair of conductors and selectively responsive to the direction and value of the current received therefrom.

8. A railway signal system comprising a stretch of railway track divided into a plurality of successive track sections, a pair of conductors for each section governed by traffic conditions in the associated section, control means for each section receiving energy from the associated pair of conductors and selectively responsive to the direction and value of the current received therefrom, means for each section governed in accordance with the condition of the associated control means for supplying the conductors for the section next in rear with energy of a particular direction and value or with energy of the same value but in the opposite direction or with energy of a different value, and traffic governing means for each section also controlled by the associated control means.

9. A railway signal system comprising a stretch of railway track divided into a plurality of successive track sections, a pair of conductors for each section governed by traffic conditions in the associated section, control means for each section receiving energy from the associated pair of conductors and selectively responsive to the direction and value of the current received therefrom, means for each section governed in accordance with the condition of the associated control means for supplying the conductors for the section next in rear with energy of a particular direction and value or with energy of the same value but in the opposite direction or with energy of a different value, and a signal for each section capable of assuming three distinctive proceed conditions also governed by the associated control means.

HOWARD A. THOMPSON.
